UNITED STATES PATENT OFFICE

2,537,000

YARN FEEDING MECHANISM FOR
KNITTING MACHINES

Edward Victor Stibbe and Bertram Henry West,
Leicester, England, assignors to G. Stibbe & Co.
Limited, Leicester, England, a British company

Application July 25, 1949, Serial No. 106,684
In Great Britain August 5, 1948

11 Claims. (Cl. 66—132)

1

This invention relates to yarn feeding mechanism for knitting machines, and has for its object to provide a simplified form of such mechanism of the type comprising positive means capable of drawing-off the yarn from its supply at varying rates on its way to the needles, and adapted to determine the said rates in accordance with variations in the tension of the yarn.

The invention consists of yarn feeding mechanism the principal feature of which is that it embodies a single tapered roller about the periphery of which the yarn is intended to be lapped or wrapped on its way to the feeder of the machine, and which is positively driven so as to exert, frictionally, a drawing-off action on the yarn and means adapted to be influenced by variations in tension of the yarn during knitting, whereby, as the result of such variations, the position of the lap or wrap of the yarn is varied lengthwise of the roller so that the lap or wrap is increased or decreased and the rate at which the yarn is drawn from the supply is correspondingly varied as occasion demands.

Conveniently the roller is of frusto-conical form and has a plain periphery. For example, a roller made of wood, metal, or of a plastic substance may be adopted. In order to enhance the frictional grip of the yarn on the roller the latter may be provided with a covering of rubber or of a material in the nature of rubber, or any other suitable frictional material not likely to have abrasive action on the yarn. Preferably, however, the tapered roller is made wholly of rubber or like material.

The invention is primarily intended for application to circular knitting machines of the independent latch or bearded needle type, but it may be applied to knitting machines of other types, in connection with which the provision of similar yarn feeding mechanism would be an advantage as compared with existing mechanisms.

In order that the invention may be more clearly understood and readily carried into practical effect, a specific example thereof applicable to a circular knitting machine of the rotary bed and independent needle type with a superstructure adapted to carry an overhead yarn supply will now be described with reference to the accompanying drawings, wherein,

Figure 1 is a general perspective view showing a portion of such a superstructure with the improved yarn feeding mechanism applied thereto,

Figure 2 is a part side elevational and part vertical sectional view of the said yarn feeding mechanism,

2

Figure 3 is a side elevational view of the mechanism, illustrating the manner in which the lapping or wrapping of the yarn is shifted axially along the tapered roller consequent upon a rocking movement of the yarn compensator,

Figure 4 is a detail vertical sectional view corresponding to the lower portion of Figure 2 showing how the appropriate yarn guide co-operates with an electrical stop motion, and

10 Figure 5 is a detail part sectional and part elevational view depicting one of the connections in the circuit of the electrical stop motion.

Like parts are designated by similar reference characters throughout the drawings.

15 Referring to Figure 1, the reference numeral 1 indicates the central vertical column of a superstructure such as is commonly mounted on the top of a circular knitting machine of the cylinder and dial type. A few of the cylinder needles of

20 the machine are shown at 2, and co-operating dial needles at 3. 4 represents a yarn feeder bracket or feeder furnished with eyes 5 through which a yarn Y drawn from a cone or other wound package such as 6 is fed to the needles at a knitting

25 location. The wound package of yarn 6 is supported upon a carrier disc 7 which is fitted with a central vertical spindle 8 for locating the said package in position. The disc 7 is in turn carried by a radial arm 9 secured at its inner end in a supporting spider or circular frame 10 fitted upon the central vertical column 1. From the package

30 6, the yarn Y extends upwardly first through a pair of slotted tensioning discs 11 and then through yarn guides 12 and 13 at the top of the superstructure from whence it then extends

35 downwards through a fixed pot eye 14 to the yarn feeding mechanism—designated generally by the reference letter A. The tensioning discs 11 are carried by a radial arm 15 secured in a holder 16

40 fixed on the vertical column 1, whilst the guides 12 and 13 consist of appropriately bent ends of a length of wire 17 secured in a further holder 18 on the upper end of the said column. From the yarn feeding mechanism A, the yarn Y extends

45 upwards again, over a guide 19 carried by the aforesaid carrier disc 7 and finally downwards through the feeder bracket 4 to the needles. In the case of a multi-feeder knitting machine there would be a plurality of yarns—one to each feeder

50—with a separate mechanism such as A for feeding each yarn.

The yarn feeding mechanism A in the particular example illustrated comprises a single frusto-conical roller 20 of solid rubber moulded or vulcanized onto a metal spindle 21. The roller

55

20 has a plain periphery. The spindle 21 is journalled in a bushed bearing 22 provided in the wall of a fixed circular casing 23 which is centrally bossed at 24 to receive the lower end of the vertical column 1. The casing 23 is fitted with a removable cover 25. The inner end of the spindle 21, which extends radially from the casing, is provided with a pinion 26 arranged in mesh with a crown wheel 27 adapted to be driven from a shaft (not shown) in turn driven from the main driving gear of the machine. The crown wheel 27 is rotatably mounted within the casing in the manner shown in Figure 2. Thus, the frusto-conical roller 20 is positively driven in a continuous manner. As will be seen from Figure 1, the roller 20 is arranged horizontally above the needles. Associated with the frusto-conical roller 20 are automatic means consisting of a yarn compensator comprising a hub 28. The hub 28 is mounted to rock about a stub axle 29 fitted on a bracket 30 carried by the superstructure aforesaid, and is provided with a counterweight 31.

Depending radially from the hub 28 normally to a point located substantially midway of the ends of the roller 20 (see Figure 3), are two closely adjacent yarn guides 32 and 33 through which the yarn Y is passed when being lapped or wrapped about the roller 20, preferably, and as shown, in a single turn or coil, during threading up. The yarn extending downwards through the pot eye 14 passes first down through the guide 32 then completely around the roller 20 and again downwards through the companion guide 33. The guides 32 and 33, which are disposed alongside the roller 20, maintain the lapping or wrapping Y¹ and consequently, on rocking of the hub 28, according to variations in the tension of the yarn, shift the lapping or wrapping axially along the roller 20 one way or the other with consequent increase or decrease in the amount of yarn lapped or wrapped and likewise a corresponding variation in the rate of drawing-off, the roller being, as previously described, positively driven. This windlass or capstan-like lapping or wrapping of the yarn about a single, positively driven, tapered or frusto-conical roller with its capacity for variation in position on the roller and resultant variation in the rate of supply under varying conditions, as aforesaid, constitutes the essential novel feature of the present invention as compared with a yarn furnishing means of known type, comprising a pair of frusto-conical toothed wheels, arranged with their axes parallel, and their teeth in mesh, so as to be adapted to measure off variable lengths of yarn according to the different points along the wheels at which yarn passes between them, as determined by automatic controlling means, including, for example, a compensator adapted to be influenced by the running yarn. The invention provides a simpler and more compact mechanism so that its adaptation to circular knitting machines of the multi-feed type in which the required rollers are arranged horizontally and radially about a common vertical axis enables considerably more feeders and yarn feeding mechanism to be provided in a machine of a given size, i. e. cylinder diameter, as compared with a mechanism which includes a pair of meshing toothed wheels, with commensurate increase in the rate of production of knitted fabric. In order to produce the rocking movement of the hub 28 necessary to shift the lapped or wrapped yarn axially of the roller 20 the said hub is furnished with an additional guide 34 which extends upwardly and is located between

the hub 28 and the yarn feeder bracket at the knitting location concerned. Between the guides 33 and 34, the yarn Y passes through a dropper guide 35 having associated therewith a contact 36 arranged in an electrical circuit including an electrical stop motion whereby, in the event of abnormalities such as yarn failure or breakage, the dropper guide 35 is released and closes the circuit, thereby energising an electro-magnet (not shown) which, in turn, operates to trip a belt striking gear or equivalent means to stop the machine. The contact 36 is adapted for co-operation with a spring contact 37 which is arranged to bear upon a metallic conductor strip or plate 38 to which is connected an insulated wire 39 in turn connected to the electro-magnet. In Figure 4, the dropper guide 35 is shown released with the circuit closed.

Thus, tracing the yarn Y from the wound package 6 it passes first through a pair of slotted tension discs 11, then through the guides 12 and 13 and the pot eye 14, thence through the lap or wrap guide 32, then in a single turn or coil around the roller 20, then through the other lap or wrap guide 33 to the yarn feeder 4 by way of the dropper guide 35, the guide 34 on the hub 28 and the guide 19, the whole being so arranged as to be adapted to enable the mechanism to function as hereinbefore described. It will be noted that the pivotal axis of the compensator is at right angles to the axis of the roller 20 so that according to the tendency of the yarn Y to vary in tension, the compensator in swinging one way or the other, will move the dependent lap or wrap guides 32 and 33 correspondingly and commensurately along the roller, as occasion demands. If desired, an auxiliary yarn guide may be provided adjacent to the dropper guide 35 so that the latter is held up while the yarn is intact.

40 The mechanism provided by the invention may be applied to circular and other appropriate knitting machines employed in the manufacture of body fabric, garments or garment lengths, as well as to machines for producing stockings, socks and like knitted articles. Moreover the invention may be applied to circular knitting machines with stationary needle beds and movable cam systems.

What we claim then is:

1. In a knitting machine, in combination, a 50 series of needles, a structure adapted to carry a supply of yarn, a feeder through which yarn from the said supply is passed to the needles at a knitting location, and a yarn feeding mechanism comprising a single tapered roller about the periphery of which yarn is wrapped on its way to the said feeder, means for positively driving the tapered roller so as to exert, frictionally, a drawing-off action on the yarn, guides adapted to maintain the wrap of the yarn about the 55 tapered roller, and a movable component which carries the said wrap guides and is adapted to be influenced by variations in tension of the yarn during knitting whereby, as the result of such variations, the wrap guides are displaced to vary the position of the wrap of the yarn lengthwise of the tapered roller so that the wrap is increased or decreased and the rate at which the yarn is drawn from the supply is correspondingly varied as occasion demands.

70 2. In a knitting machine, in combination, a series of needles, a structure adapted to carry a supply of yarn, a feeder through which yarn from the said supply is passed to the needles at a knitting location, and a yarn feeding mechanism comprising a single frusto-conical roller

having a plain periphery about which yarn is wrapped on its way to the said feeder, means for positively driving the tapered roller so as to exert, frictionally, a drawing-off action on the yarn, guides adapted to maintain the wrap of the yarn about the frusto-conical roller, and a movable component which carries the said wrap guides and is adapted to be influenced by variations in tension of the yarn during knitting whereby, as the result of such variations, the wrap guides are displaced to vary the position of the wrap of the yarn lengthwise of the frusto-conical roller so that the wrap is increased or decreased and the rate at which the yarn is drawn from the supply is correspondingly varied as occasion demands.

3. A combination according to claim 1, wherein the tapered roller is made wholly of rubber.

4. In a knitting machine, in combination, a series of needles, a structure adapted to carry a supply of yarn, a feeder through which yarn from the said supply is passed to the needles at a knitting location, and a yarn feeding mechanism comprising a single tapered roller about the periphery of which yarn is wrapped on its way to the said feeder, means for positively driving the tapered roller so as to exert, frictionally, a drawing-off action on the yarn, guides adapted to maintain the wrap of the yarn about the tapered roller, a rocking component which carries the said wrap guides and is mounted for rocking movement upon a pivotal axis, and a further guide on the rocking component for engagement with the run of the yarn between the wrap guides and the aforesaid feeder so that the rocking component is influenced and caused to rock back and forth by variations in the tension of the yarn during knitting whereby, as the result of such variations, the wrap guides are displaced to vary the position of the wrap of the yarn lengthwise of the tapered roller so that the wrap is increased or decreased and the rate at which the yarn is drawn from the supply is correspondingly varied as occasion demands.

5. In a knitting machine, in combination, a series of needles, a structure adapted to carry a supply of yarn, a feeder through which yarn from the said supply is passed to the needles at a knitting location, and a yarn feeding mechanism comprising a single tapered roller about the periphery of which yarn is wrapped on its way to the said feeder, means for positively driving the tapered roller so as to exert, frictionally, a drawing-off action on the yarn, guides adapted to maintain the wrap of the yarn about the tapered roller, a rocking component which carries the said wrap guides and is mounted for rocking movement upon a pivotal axis, a further guide on the rocking component for engagement with the run of the yarn between the wrap guides and the aforesaid feeder so that the rocking component is influenced and caused to rock back and forth by variations in the tension of the yarn during knitting whereby, as the result of such variations, the wrap guides are displaced to vary the position of the wrap of the yarn lengthwise of the tapered roller so that the wrap is increased or decreased and the rate at which the yarn is drawn from the supply is correspondingly varied as occasion demands and a counterweight which is provided on the rocking component.

6. In a knitting machine, in combination, a series of needles, a structure adapted to carry a supply of yarn, a feeder through which yarn

from the said supply is passed to the needles at a knitting location, and a yarn feeding mechanism comprising a single tapered roller about the periphery of which yarn is wrapped on its way to the said feeder, means for positively driving the tapered roller so as to exert, frictionally, a drawing-off action on the yarn, guides adapted to maintain the wrap of the yarn about the tapered roller, a movable component which carries the said wrap guides and is adapted to be influenced by variations in tension of the yarn during knitting whereby, as the result of such variations, the wrap guides are displaced to vary the position of the wrap of the yarn lengthwise of the tapered roller so that the wrap is increased or decreased and the rate at which the yarn is drawn from the supply is correspondingly varied as occasion demands, a yarn guide in the form of a dropper for engagement with the run of the yarn between the wrap guides and the feeder, the said dropper being normally held in an idle position by the yarn but adapted to be released in the event of abnormalities occurring in the yarn feed, and means adapted, upon release of said dropper, to initiate stoppage of the machine.

7. In a knitting machine, in combination, a series of needles, a structure adapted to carry a supply of yarn, a feeder through which yarn from the said supply is passed to the needles at a knitting location, and a yarn feeding mechanism comprising a single tapered roller about the periphery of which yarn is wrapped on its way to the said feeder, means for positively driving the tapered roller so as to exert, frictionally, a drawing-off action on the yarn, guides adapted to maintain the wrap of the yarn about the tapered roller, a rocking component which carries the said wrap guides and is mounted for rocking movement upon a pivotal axis, a further guide on the rocking component for engagement with the run of the yarn between the wrap guides and the aforesaid feeder so that the rocking component is influenced and caused to rock back and forth by variations in the tension of the yarn during knitting whereby, as the result of such variations, the wrap guides are displaced to vary the position of the wrap of the yarn lengthwise of the tapered roller so that the wrap is increased or decreased and the rate at which the yarn is drawn from the supply is correspondingly varied as occasion demands, a yarn guide in the form of a dropper for engagement with the run of the yarn between the wrap guides and the further guide employed to produce the rocking movements of the rocking component, the said dropper being normally held in an idle position by the running yarn but adapted to be released in the event of abnormalities occurring in the yarn feed, and a pair of electrical contacts associated with the dropper and adapted to be brought into contact in the event of the dropper being released for the purpose of initiating stoppage of the machine.

8. In a circular knitting machine, in combination, a series of needles, a superstructure adapted to carry an overhead supply of yarn, a feeder through which yarn from the said supply is passed to the needles at a knitting location, and a yarn feeding mechanism comprising a single tapered roller about the periphery of which yarn is wrapped on its way to the said feeder, the said roller being arranged above the needles, horizontally and radially with respect to the central axis of the machine, gearing for

positively driving the tapered roller from the main drive of the machine so as to exert, frictionally, a drawing-off action on the yarn, guides adapted to maintain the wrap of the yarn about the tapered roller, and a movable component which carries the said wrap guides and is adapted to be influenced by variations in tension of the yarn during knitting whereby, as the result of such variations, the wrap guides are displaced to vary the position of the wrap of the yarn lengthwise of the tapered roller so that the wrap is increased or decreased and the rate at which the yarn is drawn from the supply is correspondingly varied as occasion demands.

9. In a knitting machine, in combination, a series of needles, a structure adapted to carry a supply of yarn, a feeder through which yarn from the said supply is passed to the needles at a knitting location, and a yarn feeding mechanism comprising a single tapered roller about the periphery of which yarn is wrapped on its way to the said feeder, means for positively driving the tapered roller so as to exert, frictionally, a drawing-off action on the yarn, two closely adjacent yarn guides through which the yarn is passed when being wrapped about the tapered roller during threading up, said guides being adapted to maintain the wrap of the yarn about the tapered roller, and a component from which the said two guides depend radially, this component being mounted for rocking movement upon a pivotal axis and adapted to be influenced by variations in tension of the yarn during knitting whereby, as the result of such variations, the wrap guides are displaced to vary the position of the wrap of the yarn lengthwise of the tapered roller so that the wrap is increased or decreased and the rate at which the yarn is drawn from the supply is correspondingly varied as occasion demands.

10. A combination according to claim 4, wherein the pivotal axis of the rocking component is at right angles to the axis of the tapered roller.

11. In a circular knitting machine, in combination, a series of needles, a superstructure adapted to carry an overhead supply of yarn, a feeder through which yarn from the said supply is passed to the needles at a knitting location, and a yarn feeding mechanism comprising a single tapered roller about the periphery of which yarn is wrapped on its way to the said feeder, two closely adjacent yarn guides adapted to maintain the wrap of the yarn about the tapered roller, a component from which the said two guides depend radially, this component being mounted for rocking movement about a pivotal axis, and an upwardly extending guide on the rocking component, the yarn from the supply carried by the superstructure being passed down through one of the two wrap guides, then in a single turn around the tapered roller, then through the other wrap guide, up through the upwardly extending guide and from thence through the feeder to the needles, so that the rocking component is influenced and caused to rock back and forth by variations in the tension of the yarn during knitting whereby, as the result of such variations, the wrap guides are displaced to vary the position of the wrap of the yarn lengthwise of the tapered roller so that the wrap is increased or decreased and the rate at which the yarn is drawn from the supply is correspondingly varied as occasion demands.
